UNITED STATES PATENT OFFICE.

CHARLES E. BRADSHAW, OF CLEVELAND, OHIO.

COMBINATION HAIR DRIER AND COMB.

SPECIFICATION forming part of Letters Patent No. 701,673, dated June 3, 1902.

Application filed October 4, 1901. Serial No. 77,613. (No model.)

To all whom it may concern:

Be it known that I, CHARLES E. BRADSHAW, a citizen of the United States, residing at Cleveland, in the county of Cuyahoga and State of Ohio, have invented a new and useful Improvement in a Combination Hair Drier and Comb, of which the following is a specification.

This invention relates to toilet articles for 10 combing and drying the hair, and has for its object the production of a device of this character which is simple in construction and convenient and effective in operation. This object I attain by the structure shown in the accompanying drawings, in which—

Figure 1 shows a longitudinal section through the center of my new comb and hair-drier. Fig. 2 is a plan view of the same, showing the preferred arrangement of the comb-teeth. Fig. 3 is a perspective view of a form of key by means of which the heating device may be safely and conveniently handled; and Fig. 4 shows the heating device resting on the globe for a gas-light, where it is being heated 25 by means of the gas-jet.

Similar reference characters designate corresponding parts throughout the several views of the drawings.

Heretofore it has been a very difficult matter for a woman to thoroughly dry her hair after washing the same, and as a consequence the hair is often permitted to go only partially dried, which generally results in a severe cold. It is the object of my invention to enable a 35 woman with the heaviest head of hair to not only quickly dry the same, but to thoroughly comb and crimp it while it is drying.

In the drawings forming part of this application, 1 designates a hollow metallic main body, which I shall call the "shell," to which 40 suitably secured a handle 2, the outside portion of which is covered with a material which, relatively to the shell, is a con-conductor of heat. The shell 1, which is preferably of a 45 double-convex or oval shape, is composed of a lower and an upper part 3 and 4, respectively, said parts being suitably secured together, as by a hinge, at 5. The handle 2 is secured to the lower part only of the shell in order that 50 the upper part may be turned backwardly therefrom to give access to the interior of the shell. To hold the upper part closed, it is

formed with a projecting lug 6 where it contacts with the handle, and mounted for rotation upon the handle next the body or shell 1 55 is a ferrule or thimble 8, which has a notch 9 of substantially the same shape and size as the lug 6, through which the said lug is adapted to pass when the upper part 4 is being closed. After this part is closed it is secured in this 60 position by simply turning the ferrule 8 to bring its notch out of register with the lug.

Projecting from the shell about its central portion, as shown in Figs. 1 and 2, are metallic comb-teeth 10, which are preferably arranged 65 in rows, of which three are shown in the drawings. While any number of teeth may be employed, I have found three rows to be sufficient, and I therefore prefer to use that number. In fact, for drying the hair it is not necessary 70 that any teeth at all be provided.

The device is heated, preferably, by placing a hot body or substance within the interior of the shell 1, which will receive its heat from the said body. Any suitable material 75 may be used for this purpose, and I do not desire to limit my invention to the use of any particular substance. I have found, however, that soapstone gives excellent results. In Fig. 1 I have shown a body at 11, which is 80 mounted within the shell 1, and this body also appears in Fig. 4, where it is shown arranged over a gas-jet for heating. In order that it may be held centrally within the shell and may also be supported by the globe 12 for the 85 gas-jet 13, I provide it with diametrically-projecting pins 14. The lower part 3 of the shell has at a point in front of the hinge 5 a lug 15, in which is formed a socket for the reception of the end of one of the pins 14, while 90 a notch is made at the base of the handle for the reception of the end of the other pin, the location of the socket and the notch being such that the body 11 is centrally supported within the shell 1. To prevent the body 11 95 from turning within the shell, I prefer to flatten the end of the pin which enters the notch in the handle, as indicated at Fig. 4.

As will be understood, it would be difficult to handle the body 11 because of its heat if 100 some means were not provided whereby one could place it in position over the heating device and also in the shell without touching it with the hand. For this purpose I use a

key or handle 16, in the end of which is formed a socket 17 to fit the flattened end of the pin 14. By simply placing this key over the end of the pin the body 11 may be moved about 5 as desired.

In order to provide a tight joint between the lower and upper parts of the shell, I form a projecting flange 18 on one of said parts, over which the rim of the opposite part is 10 adapted to fit closely.

While I have shown and described means for heating the shell from within, it may be heated by placing it directly over the gas-jet or by applying heat to it externally in any 15 other manner.

As has been stated, it is not necessary for drying the hair that the shell have any teeth at all, although the teeth, being hot themselves, will hasten the drying. Moreover, I 20 have discovered that if the hair is dried while it is zigzagged among the teeth of the comb it will be crimped and will take on the light and fluffy appearance which is now secured by means of curling-irons, &c.

25 Having thus described my invention, what I claim as new, and desire to secure by Letters Patent, is—

1. In a device for drying the hair, a hollow metallic shell, a solid body within the shell 30 for heating the same, said body being smaller than the hollow of the shell, pins secured to said body for centrally supporting it within the shell, and a handle secured to the shell, for the purpose specified.

35 2. In a device for drying the hair, a hollow oval-shaped metallic shell composed of two parts hinged together, teeth projecting from said shell, means adapted for being heated and for insertion within the hollow of the 40 shell, means for holding the parts of the shell closed, and a handle of relatively non-conducting material secured to one of the parts of the shell, for the purpose specified.

3. In a device of the character described, a 45 hollow metallic shell composed of two parts hinged together, a body adapted for heating

and for insertion within the hollow of the shell, pins projecting from said body by means of which it is supported within the shell, and a handle of relatively non-conducting mate- 50 rial secured to one of the parts of the shell.

4. In a device of the character described, a hollow metallic shell composed of two parts hinged together, a body adapted for being heated and for insertion within the hollow of 55 the shell, pins projecting from said body by means of which it is supported within the shell, a plurality of rows of comb-teeth projecting from the parts of the shell, and a handle secured to the shell, for the purpose speci- 60 fied.

5. In a device of the character described, a hollow metallic shell composed of two parts hinged together, comb-teeth projecting from the shell, a handle of relatively non-conduct- 65 ing material secured to one part, a ferrule rotatably mounted on the handle adjacent the shell, said ferrule having a notch, a lug on the hinged part of the shell adapted to enter the notch, for the purpose specified, and means 70 for heating the shell.

6. In a device of the character described, a hollow metallic shell composed of two parts hinged together, a handle of relatively non-conducting material secured to one part, a 75 ferrule rotatably mounted on the handle adjacent the shell, said ferrule having a notch, a lug on the hinged part of the shell adapted to enter the notch, for the purpose specified, comb-teeth projecting from the parts of the 80 shell, a body adapted for being heated and for insertion within the hollow of the shell, and pins projecting from said body by means of which it is supported within the shell, sub- stantially as described. 85

In testimony whereof I affix my signature in the presence of two witnesses.

CHARLES E. BRADSHAW.
